UNITED STATES PATENT OFFICE.

DAVID A. PROWS, OF CASTLEGATE, UTAH.

WASHING-MACHINE.

1,149,947.

Specification of Letters Patent. Patented Aug. 10, 1915.

Application filed January 8, 1915. Serial No. 1,188.

To all whom it may concern:

Be it known that I, DAVID A. PROWS, a citizen of the United States, residing at Castlegate, in the county of Carbon and

5 State of Utah, have invented certain new and useful Improvements in Washing-Machines; and I do hereby declare the following to be a full, clear, and exact description of the invention, such as will enable others 10 skilled in the art to which it appertains to make and use the same.

This invention relates to new and useful improvements in washing machines, and has for one of the objects to provide a device 15 whereby the clothes will be reciprocated within the tub.

A further object of this invention is to provide an efficient means for reciprocating the clothes as above stated.

20 A still further object of this invention is to provide a two-part tub, forming two separate compartments by a suitable partition. This partition is provided with means and also the body walls of the tub for removing 25 the dirt from the clothes.

A still further object of this invention is to provide a hand power operating mechanism whereby the rubbers may be reciprocated.

30 A further object of this invention is to provide a washing machine of the above stated character which shall be simple, durable, and efficient, which may be operated with comparatively little physical effort, 35 and which may be manufactured and sold at a comparatively low cost.

With the above and other objects in view, the invention consists in the novel construction and arrangement of parts hereinafter 40 described and claimed, and fully illustrated in the accompanying drawings, wherein,

Figure 1 is a sectional view taken on the vertical plane extending centrally and transversely through the washing machine constructed in accordance with my invention, 45 Fig. 2 is a top plan view of the washing machine, a portion of the cover being broken away to illustrate parts of the rubbing surface of the tub, Fig. 3 is a sectional view 50 taken on the horizontal plane indicated by the line 2-2 of Fig. 1 and looking in the

direction indicated by the arrow, and Fig. 4 is a sectional view taken on a plane extending vertically and transversely through one of the rubbers. 55

Similar letters of reference denote corresponding parts in all of the figures.

The numeral 1 designates a substantially semicylindrical tub having a curved body wall 2. The curved body wall 2 is provided 60 with a plurality of longitudinal ribs 3 secured to the inner surface thereof and forming a corrugated rubbing surface, said longitudinal ribs having their upper surfaces curved or rounded so as to prevent the 65 clothes from being torn during the washing operation. A pair of head or end walls 4 are secured to the edges of the curved body wall 2. Two pair of legs 5 are secured to the head or end walls 4 and diverge outwardly from the top center edge of said head or end walls 4, providing a substantial and strong supporting means for the 70 tub.

A strip 6 is secured to the curved body wall 75 2 adjacent the bottom of the tub and is provided with a plurality of sockets 7 in the top edges thereof. A second strip 8 is secured to the curved body wall 2 adjacent the top edge of the tub and is in vertical alignment with the strip 6. The strip 8 is provided with a plurality of sockets 9 in the lower edge thereof. A plurality of rollers 10 are provided with reduced ends 12 which are journaled in the sockets 7 and 9 of the 80 strips 6 and 8. This construction provides an efficient transverse partition to the tub 1, dividing said tub into two compartments.

The rollers 10 are journaled in the strips 6 and 8 and are in spaced relation to permit 90 the water to pass freely from one compartment to the other. The vertical rollers 10 also provide a vertical rubbing surface for the clothes when they are being reciprocated within the tub 1. Another advantage of the 95 rollers 10 is that they are journaled within the strips 6 and 8 so that they will rotate under contact by the clothes while the latter are being reciprocated providing a rubbing surface which will not be destructive to the clothes. A pair of longitudinal strips 13 are secured to the top edges of the

made in the details of construction without departing from the spirit and scope of this invention, and it is therefore to be understood that this invention is not to be limited 5 to the specific construction shown and described.

What I claim is:

1. A washing machine comprising a semi-cylindrical tub, said tub provided with a 10 curved body wall, a pair of head or end walls secured to said curved body wall, means for supporting said tub, a plurality of longitudinal slats secured to the inner surfaces of the curved body wall, a transverse strip secured to the center of said 15 curved body wall adjacent the bottom thereof, said transverse strip provided with a plurality of sockets in the upper edge thereof, a second transverse strip secured adjacent the top edges of said curved body walls 20 and in vertical alinement with the first transverse strip, said second transverse strip provided with a plurality of sockets in the lower edge thereof, a plurality of rods provided with reduced ends adapted to be journaled within the sockets of both of said 25 transverse strips providing means whereby said rods may rotate in either direction, a top hingedly secured to said tub, a pair of rubbers reciprocally mounted within said tub and adapted to be supported by the top, and means for reciprocating said rubbers.

2. A washing machine comprising a substantially semicylindrical tub, a transverse 35 partition secured within the said tub, a plurality of longitudinal slats secured to the curved body walls of said tub, means for reinforcing said transverse partition, means for supporting said tub, means for securing 40 said substantially semicylindrical tub together, a top hingedly secured to the said substantially semicylindrical tub, said top provided with a plurality of elongated slots, said slots being in longitudinal alinement 45 with each other, a plurality of bearings secured to the said top adjacent the edges of said elongated slots, a pair of U-shaped supporting levers adapted to oscillate within said bearings and extending downwardly 50 through the elongated slots in said top, a pair of rubbers secured to the lower ends of said U-shaped supporting levers, the upper ends of said U-shaped supporting levers being bent to form crank members, means 55 for oscillating said U-shaped supporting levers, and means for locking the top to said tub.

3. A washing machine comprising a substantially semicylindrical tub, means for 60 supporting said tub, means for securing said tub together, means for partitioning said tub into two compartments, corrugated surfaces formed within said tub, a top hingedly secured to said tub, said top provided with 65 a plurality of elongated slots therein, a plu-

rality of bearings secured to the top adjacent said elongated slots, a pair of U-shaped supporting levers adapted to extend through said slots, a crank member formed on the upper end of each of the U-shaped levers, 70 a pair of rubbers secured to the lower ends of said U-shaped supporting levers, a plurality of brackets secured longitudinally of the top adjacent the hinged end thereof, said brackets provided with bearings on the 75 upper surfaces thereof, one of said brackets provided with a second bearing on one of the sides thereof, one of said brackets being of shorter height and provided with a bearing on the upper end thereof and in alignment with the bearing formed on the side of one of said brackets, a compound crank shaft rotatably mounted in the bearings on said bracket, means for rotating the shaft, means for connecting the said compound 80 shaft with said crank members, and means for locking said top to said tub.

4. A washing machine comprising a substantially semicylindrical tub, means for supporting said tub, means for securing said tub together, means for partitioning said tub into two compartments, a top hingedly secured to said tub, said top provided with a plurality of elongated slots therein, a plurality of bearings secured to said top adjacent the elongated slots, a pair of U-shaped supporting levers adapted to oscillate in said bearings and pass downwardly through said elongated slots, a pair of rubbers secured to the ends of said U-shaped supporting levers, a crank member formed on the upper end of each of said U-shaped members, a plurality of brackets secured to said tub, a compound crank shaft journaled in said brackets, a pair of connecting rods 100 adapted to connect the outer cranks of the compound crank shaft to said crank members, means for rotating said compound crank shaft, and means for locking said top to said tub.

5. A washing machine comprising a substantially semicylindrical tub, means for supporting said tub, means for securing said tub together, means for partitioning said tub into two compartments, a top hingedly secured to said tub, a pair of U-shaped supporting levers adapted to be supported by said top and the lower ends adapted to extend therethrough, a pair of rubbers secured to the lower ends of said U-shaped supporting levers, a pair of crank members formed on the upper ends of said U-shaped supporting levers, a compound crank shaft journaled upon said top, means for connecting said crank members to the compound crank shaft, a U-shaped bracket secured to one edge of said top, a cylindrical member pivotally secured to said U-shaped bracket, a flange formed on one side of said cylindrical member and provided with a plu- 110 115 120 125 130

rality of apertures therein, a pitman adapted to be journaled within said apertures and connected to the center crank of said compound crank arm forming means whereby said rubbers may be reciprocated within the tub, and means for locking the top to said tub.

Copies of this patent may be obtained for five cents each, by addressing the "Commissioner of Patents, Washington, D. C."

In testimony whereof I affix my signature in presence of two witnesses.

DAVID A. PROWS.
